UNITED STATES PATENT OFFICE.

WILLIAM BEALL GRAY, OF LOUISVILLE, KENTUCKY, ASSIGNOR TO MARTIN J. BANNON, OF LOUISVILLE, KENTUCKY.

PIPE-SUPPORT.

1,110,130.

Specification of Letters Patent.

Patented Sept. 8, 1914.

Application filed April 18, 1914. Serial No. 832,790.

To all whom it may concern:

Be it known that I, WILLIAM BEALL GRAY, a citizen of the United States, and a resident of Louisville, in the county of Jefferson and State of Kentucky, have invented a new and useful Improvement in Pipe-Supports, of which the following is a specification.

My invention is an improvement in pipe supports, and has for its object to provide a support for interposition between pipes, such as heating pipes, and the insulating conduit within which the pipe is laid, for supporting the pipe in such manner that it may move during expansion and contraction without any danger of buckling or bending of the pipe or injury to the conduit, and wherein the arrangement is such that the parts always occupy a definite position with respect to each other whatever the movement.

In the drawings:—Figure 1 is a transverse vertical section through the support with the supporting conduit in end view, Fig. 2 is a partial longitudinal vertical section, Fig. 3 is a perspective view of the support, Fig. 4 is a similar view of another embodiment of the invention, Fig. 5 is a partial longitudinal vertical section, Fig. 6 is an end view with parts in section of another embodiment of the invention, and Fig. 7 is a perspective view of a stilt.

In the embodiment of the invention shown in Figs. 1 to 3, the improved support is shown in connection with a pipe 1, having an insulating covering 2, and arranged within a conduit 3. The conduit is composed of sections, each section having at one end a radially offset flange 4, for receiving the end of the adjacent section, and the conduit is provided with internal ribs 5, each of which is provided at spaced intervals with pairs of notches 6, the notches of the ribs registering. The support consists of three elements, namely, a saddle in which the pipe rests, a cradle for engaging the conduit, and a connecting member arranged between the saddle and the cradle and connecting them in such manner that while they may move longitudinally with respect to each other, they must retain at all times a predetermined relative position with respect to each other. The saddle is in the form of a plate 7, having at each side edge a depending flange 8, and provided on its under face between the flanges with a plurality of series of rack

teeth 9. The series of rack teeth are separated from each other and the teeth of the series are in register. The plate 7 is provided on its upper face with a plurality of pairs of chairs, the members of the pairs being opposite each other and one pair being arranged at each end of the plate. Each of the chairs as shown more especially in Fig. 3 consists of two parallel spaced walls, which are connected by a web at their outer edges, 65 the walls and web constituting a base 10, and the web is extended upward in a leaf 11. The upper edges of the wall and the leaf are inclined as shown, and the upper surface of each pair of chairs is formed on an arc, 70 whose center is the center of the pipe to be supported. Each of the leaves 11 is provided with a transverse slot 12, near its outer end, and the upper face of the leaf is rabbed as shown at 13, from the slot to the 75 upper end thereof. The slots and the rabbed portions are for engagement by the ends of a holding band 14, which is passed around the pipe 1, beneath the covering 2, to bind the pipe to the saddle. The cradle 80 consists of a frame 15 of substantially rectangular shape and provided with a pocket or depression 16, at its center. The bottom of the pocket is provided with a longitudinally extending slot 17 and with a series of 85 teeth 18, on each side of the slot, the teeth of the series registering. The spacing of teeth in the cradle pocket corresponds to the spacing of the teeth of the saddle, and the cradle is provided with laterally extending 90 supporting fingers 19, at each side and at the ends of the sides. The supporting fingers have their under sides rounded as shown in Figs. 2 and 3, except a slight facet at bottom, and the said fingers are adapted to engage the pockets 6 of the ribs 5, before mentioned, to support the cradle between the ribs and above the bottom of the conduit, 95 said fingers being provided for locking down by groove or by oblique face as dotted in at 19^a, Fig. 3. A plurality of toothed rollers 20 is arranged between the saddle and the cradle within the pocket on the large sizes and the teeth of each roller mesh with the adjacent series of teeth 9 and 18 of the 105 saddle and cradle. The saddle is provided with a depending web 21 between the adjacent ends of the rollers, for separating the rollers, and the rollers are of such length that they will fit between the flanges 8 and 110

the web, and will move smoothly when the pipe expands or contracts. It is obvious that the web 21 might be omitted, and that a single roller might be used, of a length to extend from near one web 8 to near the other web, the roller having a series of teeth at each end or continuous teeth.

In Fig. 4, the same saddle is used, and the same roller or rollers, but the cradle is somewhat different from that shown in Figs. 1 to 3, and is supported in a different manner. The cradle comprises a substantially rectangular frame 22, having a central depending pocket 23, and the cradle is provided with a plurality of longitudinal series of transverse teeth 24 on the pocket. The saddle and the cradle are connected by the rollers 20, or by a single roller, as may be desired, and at each end the cradle is provided with an arc-shaped extension 25, which is adapted to engage over a shaft or cylindrical support 26. The under face of each of the extensions 25 is shaped to fit the largest size of shaft used rather closely, and smoothly as shown in Figs. 4 and 5, and the ends of the shafts or supports are adapted to engage the notches 6 of the supporting ribs 5 of the conduit.

The above-described construction is especially adapted for supporting more than one pipe in a single conduit. It will be obvious that the conduit may be of any desired size and that the shafts or supports 26 will be of a length to extend from one rib of the conduit to the other. With this construction of support, it is not necessary to provide every conduit section with the ribs 5 and the notches 6. Every fourth or fifth conduit section will be a rest section and will be provided with the ribs and notches as shown in Figs 1 and 2. The intermediate lengths or sections of conduit may be plain internally, only enough rest lengths being inserted to properly support the pipe.

In Fig. 6, the cradle consists of a plate 27, having at each side edge a depending flange or rib 28. On its under face the plate is provided with four longitudinal series of transverse teeth 29, the series being spaced apart from each other as shown. On its upper face the plate is provided with the chairs 29, having the leaves 30, and the pipe 31 rests upon the upper ends of the chairs, and is bound to the chairs by the bands 31 in the usual manner. Shafts or cylindrical supports 32 are arranged in the conduit 33, the ends of the supports resting in notches 34 in the ribs 35. Two of the cradles shown in Figs. 4 and 5 are arranged in the conduit, the arc-shaped or curved extensions of the cradles engaging the shafts. The cradles shown in Fig. 6 it will be noticed are provided with slots 36 between the series of teeth 24, and the cradles are arranged along side each other. Two series of teeth of the

saddle register with the teeth of each cradle, and a single roller or two rollers 20 may be used in each.

In Fig. 7, is shown a stilt for interpolation between the pipe to be supported and the chairs to permit the thickness of the insulation to be varied abnormally if necessary. When the saddle is arranged to support a certain character of pipe, having a certain predetermined depth of insulation, and it is desired to support a pipe having a much greater depth of insulation, the stilt may be interposed between the saddle and the pipe, the lugs on stilt locking it to the chairs. The stilt as shown, comprises a plate arched or curved longitudinally to fit the chairs. The plate is provided intermediate its ends and at its opposite sides with depending lugs 38, which are adapted to fit between the pairs of chair walls at each end of the saddle. The plate is also provided at each end with pairs of upstanding lugs 39 and 39^a, the lugs 39 being at one end and the lugs 39^a at the other, to be curved to the arc of pipe supported. The members of the pairs of lugs are at opposite sides of the plate, and the lugs in conjunction with the chair walls are adapted to extend through the insulation into contact with the outer surface of the pipe.

If desired the supporting fingers 19 of the cradle may be provided with longitudinal grooves 19^a in their outer faces for receiving locking tongues of cement to hold them in the notches of the ribs of the conduit, or the said fingers may have their outer faces inclining inwardly toward the top of the fingers for the same purpose.

I claim:

1. A pipe support for supporting insulated pipes in conduits, comprising a saddle provided at each side edge with a depending flange and at its center with a depending longitudinally extending rib, and between each flange and the rib with a longitudinal series of transverse rack teeth, the teeth of the series registering, said saddle having a plurality of pairs of chairs on its upper face, the pairs being at the ends of the saddle and the members of the pairs being spaced apart transversely of the saddle, the upper ends of the chairs being curved to fit the periphery of the pipe, each chair having a transverse slot at its upper end for engagement by a tie band, a cradle having a depressed pocket provided with a plurality of series of rack teeth registering with the teeth of the saddle, a roller arranged between the saddle and the cradle at each side of the central rib and meshing with the adjacent series of teeth of the saddle and the cradle, said cradle having at each end an arc-shaped extension adapted to engage a shaft to support the cradle.

2. A pipe support for supporting insu-

- lulated pipes in conduits, comprising a saddle provided on its under face with longitudinally extending series of rack teeth, the series registering, the saddle having upon its upper face a plurality of pairs of chairs, the members of the pairs being at opposite sides of the saddle, the upper ends of each pair of chairs being curved to fit the periphery of the pipe and each chair having an upwardly and outwardly extending leaf for engaging the pipe, the cradle having a depressed pocket provided with a series of rack teeth registering with each series of the cradle, a roller having teeth for engaging the several series, and connecting the saddle to the cradle, said cradle having at each end an arc-shaped extension adapted to engage a shaft to support the cradle, the saddle having depending flanges at its side edges for engaging the ends of the roller to limit the lateral movement of the saddle.
3. A pipe support for supporting insulated pipes in conduits, comprising a saddle provided on its under face with longitudinally extending series of rack teeth, the series registering, the saddle having upon its upper face a plurality of pairs of chairs, the members of the pairs being at opposite sides of the saddle, the upper ends of each pair of chairs being curved to fit the periphery of the pipe and each chair having an upwardly and outwardly extending leaf for engaging the pipe, the cradle having a depressed pocket provided with a series of rack teeth registering with each series of the cradle, a roller having teeth for engaging the several series, and connecting the saddle to the cradle, said cradle having at each end an arc-shaped extension adapted to engage a shaft to support the cradle.
4. A pipe support, for supporting insulated pipes in conduits, comprising a saddle provided on its under face with longitudinally extending series of rack teeth, the series registering, the saddle having upon its upper face a plurality of pairs of chairs, the members of the pairs being at opposite sides of the saddle, the upper ends of each pair of chairs being curved to fit the periphery of the pipe, the cradle having a depressed pocket provided with a series of rack teeth registering with each series of cradle, a roller having teeth for engaging the several series, and connecting the saddle to the cradle, said cradle having at each end an arc-shaped extension adapted to engage a shaft to support the cradle.
5. In a pipe support for supporting insulated pipes in conduits, a saddle comprising a plate having at each side edge a depending flange and having a plurality of series of rack teeth on its under face, the saddle having upon its upper face a plurality of pairs of chairs, the pairs being near the ends of the saddle and the members of the pairs being spaced apart transversely of the saddle, the upper ends of the chairs being curved to fit the periphery of the pipe, each chair having an upwardly and outwardly extending curved leaf for engaging the pipe, and provided with a slot for engagement by a tie band.
6. In a pipe support for supporting insulated pipes in conduits, a saddle comprising a plate having at each side edge a depending flange and having a plurality of series of rack teeth on its under face, the saddle having upon its upper face a plurality of pairs of chairs, the pairs being near the ends of the saddle and the members of the pairs being spaced apart transversely of the saddle, the upper ends of the chairs being curved to fit the periphery of the pipe, the chairs spacing the pipe above the saddle to prevent engagement of the insulating covering with the saddle, and a stilt for interposition between the pipe and each pair of chairs to provide for a thicker insulating covering, each stilt comprising a plate curved longitudinally to fit the upper ends of a pair of chairs and having depending lugs fitting between the chairs, and a pair of upstanding lugs at each end for engaging the pipe.
7. In a pipe support for supporting insulated pipes in conduits, a saddle comprising a plate having at each side edge a depending flange and having a plurality of series of rack teeth on its under face, the saddle having upon its upper face a plurality of pairs of chairs, the pairs being near the ends of the saddle and the members of the pairs being spaced apart transversely of the saddle, the upper ends of the chairs being curved to fit the periphery of the pipe, the chairs spacing the pipe above the saddle to prevent engagement of the insulating covering with the saddle, and a stilt for interposition between the pipe and each pair of chairs to provide for a thicker insulating covering.
8. In a pipe support comprising a cradle for engaging a conduit, a saddle for engaging the pipe, and a roller arranged between the saddle and the cradle, chairs on the saddle for engaging the pipe to support the pipe above the level of the saddle, the chairs being arranged in pairs and the members of the pairs being spaced apart transversely of the saddle, each pair of chairs having their upper ends curved to fit the pipe, and a stilt for interposition between each pair of extensions and the pipe, each stilt comprising a plate curved longitudinally to fit upon a pair of chairs and having at each side edge a depending lug for engaging between the members of the pair, and having at each end a pair of upstanding lugs for engaging the pipe.
9. In a pipe support, comprising a cradle for engaging a conduit, a saddle for engaging the pipe, and a roller arranged between the saddle and the members of the pairs being spaced apart transversely of the saddle, the upper ends of the chairs being curved to fit the periphery of the pipe, each chair having an upwardly and outwardly extending curved leaf for engaging the pipe, and provided with a slot for engagement by a tie band.

- the saddle and the cradle, chairs on the saddle for engaging the pipe to support the pipe above the level of the saddle, the chairs being arranged in pairs, and the members of the pairs being spaced apart transversely of the saddle, each pair of chairs having their upper ends curved to fit the pipe, and a stilt shaped to fit upon a pair of chairs for lifting the pipe above the level of the chairs.
